(57) **CLAIM**

The ornamental design for an electronic collar worn around the human neck, for wireless communication with a smart phone, as shown and described.

DESCRIPTION

FIG. 1 is a perspective view of the electronic collar; FIG. 2 is a plan view of the electronic collar; FIG. 3 is a left side elevation view of the electronic collar; FIG. 4 is a back side plan view of the electronic collar; FIG. 5 is a right side elevation view of the electronic collar; FIG. 6 is a front elevation view of the electronic collar; FIG. 7 is a backside elevation view of the electronic collar; and,

FIG. 8 is a perspective view of the electronic collar worn around the human neck.

The broken lines adjacent the shaded areas are directed to environment that are for illustrative purposes only; the broken lines form no part of the claimed design.

1 Claim, 5 Drawing Sheets
